[57] **CLAIM**

The ornamental design for a urine metering device, as shown and described.

DESCRIPTION

FIG. 1 is a perspective view of a urine metering device, showing our new design;

FIG. 2 is a perspective view of the primary collection and measuring container, shown separately for ease of illustration;

FIG. 3 is a perspective view of the overflow collection bag; and

FIG. 4 is a perspective view of the support frame, shown separately for clarity of illustration.

FIG. 1

FIG. 2

FIG. 3

FIG. 4
